TAPE FOR SLIDE FASTENERS

Noel J. Poux, Meadville, Pa., assignor to Talon, Inc., a corporation of Pennsylvania

Application November 14, 1950, Serial No. 195,617

4 Claims. (Cl. 24—205.16)

1

This invention relates to slide fasteners, and particularly to an improved stringer tape therefor and method of making the same.

A slide fastener comprises generally a pair of stringer tapes, each having a series of spaced-apart, interlocking, fastener elements attached to adjacent beaded edges thereof. Usually, such a stringer tape consists of a woven fabric tape having a beaded edge formed along one edge thereof either by sewing a pair of cords to opposite sides of the tape or by weaving a bead integral therewith. While such tapes are entirely satisfactory for most applications of slide fasteners, it has now been proposed to make such tapes of a plastic material for certain applications, and it is to such a plastic stringer tape that the present invention relates.

Accordingly, it is the general object of the present invention to provide an improved stringer tape for slide fasteners made of a plastic material having a beaded edge integrally arranged therewith.

It is another object of this invention to provide a method of making such plastic stringer tapes comprising forming the tape by extrusion and simultaneously forming the beaded edge thereon at the time of the extruding process so as to be an integral part thereof.

It is a further object of the invention to provide an improved plastic stringer tape for slide fasteners which is inexpensive and which can be easily and simply manufactured.

It is still another object of the present invention to provide a plastic stringer tape which is durable and, at the same time, sufficiently flexible for its intended use.

Various other objects and advantages of this invention will be more apparent in the course of the following specification, and will be particularly pointed out in the appended claims.

In the accompanying drawings, there is shown for the purpose of illustration, an embodiment and several modifications thereof which my invention may assume in practice.

In these drawings:

Fig. 1 is a plan view of a slide fastener having the improved stringer tape of my invention incorporated therewith;

Fig. 2 is a fragmentary plan view of my improved stringer tape of the preferred form with the cords being partially removed;

Fig. 3 is a sectional view taken on line 3—3 of Fig. 2;

Fig. 4 is a sectional view taken on line 4—4 of Fig. 1;

2

Fig. 5 is a cross sectional view of a modified form of tape in accordance with the present invention;

Fig. 6 is a cross sectional view of another modification of my invention;

Fig. 7 is a cross sectional view of still another modified form of tape of this invention;

Fig. 8 is a vertical section through an extruding press and die showing how my improved tape is made; and

Fig. 9 is a sectional view taken on line 9—9 of Fig. 8.

In Fig. 1 of the drawings, there is shown a conventional slide fastener comprising a pair of stringer tapes 2 each having beaded edges 3 arranged integrally therewith which tape, together with the beaded edge, is constructed in accordance with the present invention. There is attached to the opposed beaded edges 3 of the tapes, a series of opposed fastener elements 4 on which there is arranged for longitudinal movement therealong a slider 5 having a pull member 6 for engaging and disengaging the fastener elements in a manner well known to those skilled in the art.

According to the present invention, and referring now to Figs. 2, 3, and 4 of the drawings wherein the preferred form of my invention is illustrated, the stringer tape 2 consists of a strip of thermoplastic material, such as vinyl, polyvinyl, etc., which is formed preferably by extrusion in a manner to be explained hereinafter. This tape has preferably a relatively thick outer body portion, as at 7, and a relatively thin intermediate body portion, as at 8, for a purpose hereinafter to be described. Along the inner edge of the tape, there is arranged an enlarged portion 9 having a channel or groove 10 arranged on opposite sides thereof in each of which there is arranged preferably a fabric cord 12 so as to provide the beaded edge 3 for the attachment of the fastener elements 4 thereto. It is the purpose of the channel 10 to position the cords 12 along the edge of the tape and to aid in preventing displacement of the cords. These cords 12 may be secured adhesively to the tape after it is formed as shown, but preferably they are secured to the tape by adhesion at the time of the forming by extrusion thereof in a manner to be explained.

In Fig. 5, there is shown a slight modification of the tape of my invention. This construction is the same as the preferred form in that it has preferably a thickened outer portion, as at 13, and a relatively thin intermediate portion, as at

14. Along the outer edge, there is arranged an enlarged portion 15 which is substantially triangular shape in cross section so as to provide an arcuated shoulder 16 along the opposed sides thereof which shoulders act as seats for the cords 17 arranged therealong on opposite sides thereof.

There is shown in Fig. 6, another modified form of the present invention. In this construction, the tape again preferably has a relatively thick outer portion, as at 18, and a relatively thin intermediate portion, as at 19. The beaded edge 3 is formed integral with the tape at the time of forming or extruding so as to provide substantially a tubular portion 20 on opposite sides thereof along the edge. In other words, the beaded edge is of the same material as the body of the tape, namely, an all-plastic beaded edge.

In Fig. 7, there is shown still another modification of this invention. This construction is the same as the preferred form in that it has a pair of cords 21 arranged in channels 22 on opposite sides of the tape along the inner edge thereof. The outer portion of the tape is relatively thick and split, as at 23, so as to provide two flap portions 24 and 25, which flap portions are adapted to straddle the edge of the article to which the tape is to be applied. Between the beaded edge and this outer portion, there is preferably a relatively thin intermediate portion 26 as in the other forms of my invention.

There is shown in Figs. 8 and 9 of the drawings, apparatus for making the improved tape of the present invention. This apparatus includes an extrusion die 30 having a die opening 31 which is heated by any suitable means (not shown). It will be understood that the opening in this die conforms to the desired cross section of the tape together with the beaded edge thereof. There is provided a cylinder 32 in which the particular plastic material M from which the tape is to be made is disposed. Within this cylinder, there is arranged a feed screw 33 for delivering the material to and forcing it through the die opening 31 in a well-known manner. Preferably in either side of the die 30, there is arranged a pair of oppositely disposed openings 34 through which the cords C are introduced and delivered into and through the die opening 31. The cords are delivered from a pair of reels 35 suitably mounted opposite these openings adjacent the die.

The tape, together with the beaded edge thereof, is formed by this apparatus in the following manner. When the feed screw 33 is rotated, the plastic material M in the cylinder 32 is fed by the feed screw into the die and forced through the die opening 31 therein. At the same time, the cords C are delivered to and pulled through the die opening and integrally secured to the edge of the tape T as it is being formed and extruded at the die opening thereby producing the tape as shown in Figs. 2, 3, 5, and 7. If it is desired to produce the tape shown in Fig. 6, the cords are dispensed with and a suitable die is provided for forming the tape of the cross section shown in this view. Also, if it is desired to attach the cords to the tape to form the beaded edge after the tape is formed, again the feeding of the cords is dispensed with and a suitable die provided. The cords are then secured to the opposite sides of the tape after it has been formed preferably by any suitable adhesive.

After the tape, together with the beaded edge thereon, is formed, the tape is introduced into a conventional chain machine for attaching the

5 fastener elements 4 to the beaded edges thereof in a well-known manner so as to provide a fastener stringer as shown in Fig. 4. It will be understood that it is the purpose of the thin section immediately rearwardly of the beaded edge and the fastener elements attached thereto to provide a more flexible section at this point so that the completed fastener will operate easily and be sufficiently flexible. However, if desirable, the body portion of the tape may be of the same thickness throughout its width.

10 The cords C of the beaded edge are preferably made of twisted or interwoven strands of a fibrous material but may be made of flexible strands of a suitable plastic material, or of flexible wires.

15 As a result of my invention, it will be seen that there is provided an improved plastic stringer tape for slide fasteners which is simple and inexpensive in its manufacture. Also, there is provided a tape due to its construction which is extremely flexible and durable. It will also be seen that there is provided a plastic tape having a beaded edge integrally arranged therewith to which fastener elements can be conveniently and securely attached, and which will not readily become displaced from the body of the tape.

20 While I have shown and described an embodiment and several modifications thereof which 30 my invention may assume in practice, it will be understood that this embodiment and these modifications are merely for the purpose of illustration and description, and that other forms 35 may be devised within the scope of my invention as defined in the appended claims.

What I claim as my invention is:

1. A tape for slide fasteners of the class described comprising a strip of plastic material having a channel arranged on opposite sides thereof along one edge, a pair of fabric cords with one disposed in each of said channels and adhesively secured to said strip so as to provide a beaded edge therealong, each of said channels adapted to act as a seat for said cords so as to aid in maintaining said cords in position along said edge.

2. A tape for slide fasteners of the class described comprising a strip of plastic material having a beaded edge formed integral therewith, said beaded edge consisting of a pair of fabric cords adhesively secured to opposite sides of said strip, and means formed in said strip along said edge for aiding in seating and maintaining said cords in position therealong.

3. A tape for slide fasteners of the class described, as defined in claim 2, wherein the body of the strip at a point immediately adjacent to and inwardly of the beaded edge is thinner than the remaining portion of the strip.

4. A tape for slide fasteners of the class described comprising a strip of plastic material having a relatively thick outer body portion and a channel arranged on opposite sides of the strip along the opposite edge, said strip having a relatively thin intermediate portion between said thick outer portion and said channels, a pair of fabric cords with one disposed in each of said channels and adhesively secured to said strip so as to provide a beaded edge therealong, each of said channels adapted to act as a seat for said cords so as to aid in maintaining said cords in position along said edge.

NOEL J. POUX.
